UNITED STATES PATENT OFFICE.

WILLIAM GUIER, OF WICHITA, KANSAS.

STREET INDICATOR.

Application filed January 8, 1921. Serial No. 436,009.

To all whom it may concern:

Be it known that I, WILLIAM GUIER, a citizen of the United States, residing at Wichita, in the county of Sedgwick and State of Kansas, have invented new and useful Improvements in a Street Indicator, of which the following is a specification.

My present invention has reference to a street or station indicator for rolling stock.

10 An object is the production of simple electrically operated means which will accurately indicate the next stop of the vehicle in which the device is arranged.

15 A further object is the production of a street or station indicator which is electrically operated either from an overhead or third rail electric system, but which may be also operated by electric means arranged in the coaches of a railroad train, and by which 20 the sheet containing the names of the streets or stations will be accurately wound or unwound to positively disclose through a suitable opening in the casing therefor, the name of the next street or station at which the 25 vehicle will stop.

25 The foregoing, and many other objects which will appear as the nature of the invention is better understood, may be accomplished by a construction, combination and 30 operative arrangement of parts, such as is illustrated by the drawings.

In the drawings:—

35 Figure 1 is a diagrammatic view of a coach in which the control circuit is actuated from an overhead conductor.

Figure 2 is a similar view in which the control circuit is operated by the conductor of the third rail system.

40 Figure 3 is a view showing the arrangement of the indicator in a coach.

Figure 4 is a fragmentary elevation illustrating the contact on the trolley harp in engagement with one of the contact plates secured to a guy wire above the trolley wire.

45 Figure 5 is a detail enlarged sectional view illustrating the clutch connecting means between the sprocket wheel and the shaft of the upper roller.

Figure 5 is a fragmentary front elevation of a modified form of trolley harp which 50 may be employed.

Figure 7 is a side elevation of the construction illustrated in Figure 6.

While in the drawings I have illustrated the control circuit operable from elements on the conductor of an overhead and the conductor of a third rail or underground railway system; I desire it to be understood that contact members may be arranged at desired points on the track of a steam railroad which 60 will operate the control circuit, the said circuit, in the latter instance including therein a source of energy, such as a battery. Also while the device has been illustrated as arranged in only one coach it will be apparent 65 that the indicator may be arranged in all of the coaches making up a train.

On the overhead conductor 1, at points near a street or station, I secure on guy wires 2 that are mechanically connected with the 70 conductor 1, depending contact plates 3.

On the harp of the trolley pole 4 I secure laterally arranged upwardly extending circuit makers 5. The circuit makers include each a fixed and a movable, preferably spring 75 contact, the latter being in the path of engagement with the plates 3 and the said contacts are connected to the wires 6 and 7 of the control circuit. Between the conductors 6 and 7 there may be arranged a switch 80

8, and the conductor 6 is connected to one of the wires 9 of the operating circuit 10. The wire or conductor 7 is connected to the magnets 11 from which lead the return wire 12 that is connected to the second wire or 85 conductor 13 of the operating circuit. The

armature for the magnets 11 is indicated by the numeral 14, and is influenced by a spring 15 away from the cores of the said magnets. To the armature 14 is connected the conductor 13. The conductor 9 leads to the winding of the motor 16, the return wire, indicated by the numeral 17 having its end 90

provided with a contact 18 in the path of engagement with the armature 14 when the 95 control circuit is closed.

Before proceeding further it is to be understood that the conductors for the operating or motor circuit are connected with any desired source of electric power, such source 5 having not been deemed necessary to illustrate in the drawings.

The shaft of the motor 16 has secured thereon a pinion 19 which is in mesh with one of the pinions of a train of reduced pinions or gears 20. The shaft 21 for the lower roller 22 of the indicator sheet 23 is connected with the reducing train 20. The sheet 23 is of non-electric conducting material and has its outer face imprinted with the spaced names of streets or crossings over which the vehicle passes. The sheet and the rollers therefor are encased in a suitable housing 24 which, on the outer face thereof, has a transparent sight opening 25 whereby only one of the streets or stations marked on the sheet will be displayed at a time. The upper roller for the sheet 23 is indicated by the numeral 26, and has its shaft 27 provided on one end with a sprocket wheel 28. On the shaft 21 is a similar sprocket wheel 29. Around the sprocket wheels 28 and 29 there is loosely arranged an endless sprocket chain 30.

The sheet 23, at one of the edges thereof 30 has spaced preferably rectangular openings 31 therethrough, the said openings being disposed opposite the respective streets or stations indicated on the said sheet. On the outer face of the sheet in a line with the said openings 31 is a spring contact member 32. On the inner face of the sheet, opposite the contact member 32 is a second spring contact member 33. A conductor 34 leads from the outer contact finger 32 to the conductor 9 of the operating circuit 10, while a conductor 35 leads from the contact finger 33 to a magnet 36 that is arranged above the armature 14. From the magnet leads a conductor wire 37 that terminates in a contact 45 38 that is above and slightly to the rear of the contact 18 for the conductor 17 of the operating circuit 10. Below the magnet, but in the path of engagement therewith is a substantially V-shaped catch 39 that is influenced by a spring 40. Pivotaly supported, off of its center there is a lever 75. The sprocket wheels 28 and 29 are loosely journaled on the shafts 27 and 21, the hubs of the said wheels being provided with clutch elements 28' and 29' respectively. Keyed for slidable movement on the shafts 27 and 21 there are clutch members 76 and 77 respectively. The slideable clutch members are rounded in cross section, and are 60 centrally provided with grooves in which are received forks 78 and 79 respectively on the lever 75. It will be apparent that by shifting the lever either of the clutch members 76 or 77 will be brought to engage with the clutch faces 29' or 28' on the respective

sprocket wheels 29 or 28, so that the shafts 21 and 27 will turn to draw the sheet 23 off of one of the rollers and on to the other roller to which the said sheet is secured. In this manner, the movement of the sheet will 70 be reversed when the car has reached its terminal and is making its return trip.

The operation may be briefly described as follows. The circuit makers 5 are closed by engagement with the plates 3, closing the 75 control circuit which energizes the magnets 11 and causing the same to attract the armature 14. The armature 14 first engages the contact 18 of the conductor 17 of the operating circuit 10 closing the same and operating the motor 16 which operates the rollers of the indicator. The reducing gears permit of the rollers being slowly turned. Immediately after the armature engages the contact 18 to close the operating circuit 10, the same 80 is engaged by the substantially V-shaped catch 39, which, influenced by its spring 40 will draw the said armature into engagement with the contact 38 of the shunt circuit. When this takes place, the contact 85 fingers 33 and 32 of the shunt circuit will be brought into engagement with one of the openings in the sheet 23, causing the magnet 36 to be energized which attracts the catch 39 bringing the same out of engagement 90 with the armature 14 and permits the spring 15 to move the same away from the contact 38, thus deenergizing both the operating and shunt circuits.

The operating and shunt circuits are similar in the application of the improvement to the underground or third rail electric system as well as the arrangement of the device in the coaches of a steam railway.

In the third rail system, the conductor rail 100 41 has a contact member 43 secured thereon which is in the path of engagement with a circuit maker 44 that is connected to one of the wires 46 of the control circuit. The second wire 47 of the control circuit is connected to the contact shoe 48 of the system.

It is thought that the foregoing description, when taken in connection with the drawings will fully set forth the construction and advantages of the improvement 115 without further detail description.

In Figures 6 and 7, only one circuit maker 5 is connected to the trolley harp. The trolley pole, in the said figures is indicated by the numeral 4', the guy wires by the numeral 2', the trolley wire or conductor by the numeral 1', and the conducting wires by the numerals 6' and 7'.

The rolls may be reversed at the terminals of the line by simply reversing the motor 16.

Having thus described the invention, what I claim, is:—

In a station indicator, rolls and shafts therefor, an apertured sheet having the 130

names of stations thereon secured on the rolls for winding from one of the rolls on to the other roll, sprocket wheels loose on the shafts, a chain trained therearound, motor 5 operated means for intermittently imparting motion to one of the shafts, electrically operated means engaging the apertures in the sheet for holding the sheet from movement except when the motor is operated,

means releasing the said holding means 10 when the motor is in operation, clutch means 15
slidable on the shafts of the rolls for locking either of the sprocket wheels to its shaft, and lever means for actuating the clutch means.

In testimony whereof I affix my signature.

WILLIAM GUIER.
